UNITED STATES PATENT OFFICE.

JOHN WALDHEIM, OF ELIZABETH, NEW JERSEY, ASSIGNOR TO UNDERWOOD ELLIOTT FISHER COMPANY, OF NEW YORK, N. Y., A CORPORATION OF DELAWARE.

LATCH FOR COVERS FOR TYPEWRITING MACHINES.

Original application filed November 4, 1921, Serial No. 512,741. Divided and this application filed August 13, 1925. Serial No. 49,973.

This invention relates to casings for typewriting machines, with reference to that class in which a casing is provided with a cover, and pertains more particularly to a latch for normally retaining the casing-cover in closed position.

It is desirable to adapt the casing to use with the machine on the usual folding or collapsible desk-board. Heretofore, the casings have been provided with covers, hinged thereto at the rear, and have been provided with springs for assisting in the opening of the cover; the cover being held down against the action of such springs by gravity. As the casing is tilted with the machine, in the operation of folding the same into the desk, on arriving at a certain position, gravity may cease to be effective to hold the cover in place, and the latter, urged by its springs, or by gravity, may swing open.

An object of the present invention is the provision of means for locking the cover to the casing-body, which means may be rendered ineffective or idle during the operation of the machine, so that the cover may be opened at will, and which may be readily, and in a simple manner, rendered effective when the casing is to be folded into the desk, or otherwise tilted.

This is a division of my application, Serial No. 512,741, filed November 4, 1921 (now Patent No. 1,553,055, dated September 8, 1925).

Other features and advantages will herein-after appear.

In the accompanying drawings,

Figure 1 is a view, in side elevation, of the assembled machine and casing, the latch being disclosed in two positions.

Figure 2 is a cross-sectional view, in side elevation, through the top of the casing, to illustrate the manner of latching the cover.

The casing is shown as consisting mainly of two castings, one of which 10 constitutes the body of the casing, and the other of which 11 constitutes a cover hinged at 12 to the body-portion. As indicated at 13, the body-portion is lined with a sound-deadening material, such, for instance, as felt; and, as indicated at 14, the cover is similarly lined. The body-portion of the casing is shown as having a floor or bottom 15, secured to the casting of the casing-body in any suitable manner; and the casing, as a whole, rests upon a platform

or drop leaf 16, which may be folded or collapsed into a typewriter desk in the usual manner.

The main frame 17 of the typewriting machine, indicated in dotted lines in Figure 1, is supported by front and rear feet 18 and 19. The keyboard-extension 20 of the typewriting machine projects through a suitable opening in the front wall of the casing, and suitable sound-deadening linings (not shown) are provided at the front of the casing. The typewriting machine is shown as anchored by bolts 21 in much the usual way to the platform 16. The platform 16 and felt bottom of the casings are perforated for loose passage therethrough of the bolts 21; and, to prevent emission of sound through the bolt-openings, washers 22, of felt or other sound-proof material, are inserted under the heads 23 of the bolts. The bolts 21 thread into the usual lugs 24 on the frame 17 of the typewriter. In the present instance, the casing, not being liftable independently of the typewriting machine, is therefore indirectly held to the platform 16 by the bolts 21.

For assisting in the opening of the casing-cover, there is provided, at each side of the casing, a spring (not shown), concealed within a cylinder 25, which spring bears at one end against one end of its cylinder, and at its other end against a piston on a rod 26. The rod 26 is secured at 27 to the casing-cover; and the cylinder, in which it slides, is secured at 28 to the casing-body. Brackets 29 and 30 attached, respectively, to the cover and the casing-body, serve as anchors for the rods 26 and cylinders 25, respectively. Metal strips 31, 32, laid against the inside of the edges of the linings 13 and 14, respectively, and running longitudinally of such lining-edges, are secured to the body and cover castings by screws 33, and thus serve to hold the linings at their edges.

Normally, gravity suffices to hold the cover closed; in which position (see Figure 2) the lining-strips 14 at the sides of the cover rest upon the casting 10 of the body-part. Ribs 35, formed in the side or end walls of the cover-casting, serve as reinforcements therefor, and as abutments for the lining-strips 14. When the casing with the machine is folded back into the desk a sufficient distance, gravity may no longer serve to hold the cover to its seat on the casing-body; and, at such times, to hold

the cover to the casing-body, a lock or detent is provided. This lock or detent consists of a spring-arm 37, pivoted at 38 to the casing-cover, to have movement thereon to the full 5 and dotted line positions of Figure 1. The distal end of the spring-arm 37 carries a bolt or lock-pin 39. Normally, that is to say, when the machine is in position for operation, and when it may be desired to open the cover, for 10 any purpose, the arm 37 is in the full line or Figure 1 position. In this position, it is sprung or bent out, with the pin or bolt 39 centered and resting in idle position in a recess 40, located in the cover end wall. Before 15 the machine and casing are folded back into the desk, however, the arm 37 is swung to the dotted line, Figure 1, position, at which time, the bolt 39 is brought into registration with a hole 41, which passes entirely through the 20 end wall of the cover, and which hole 41 is in registration with a hole 42 in the end wall of the casing-body. At this time, the spring-action of the arm 37 causes the bolt 39 to enter the holes 41 and 42, thereby locking the cover 25 against movement on its hinge 12.

Variations may be resorted to within the scope of the invention, and portions of the improvements may be used without others.

Having thus described my invention, I 30 claim:

1. The combination with a casing having a cover hinged thereto, of a flexible and shiftable arm pivoted to one side of said cover and provided with a projection thereon generally 35 parallel to said pivot, there being corresponding apertures in the side of said cover and said casing registering with each other in closed position of the cover and normally retained in registration by said arm-projection passing 40 therethrough, said arm being conditioned to

be first withdrawn by flexure thereof to withdraw said projection from said apertures, and thereafter shiftable about said pivot to shift and thereby displace said projection from said apertures to an idle position. 45

2. The combination with a casing having a cover hinged thereto, of a flexible and shiftable arm pivoted to one side of said cover and provided with a projection thereon generally parallel to said pivot, there being corresponding apertures in the side of said cover and said casing registering with each other in closed position of the cover and normally retained in registration by said arm-projection passing therethrough, said arm being conditioned to be first withdrawn by flexure thereof to withdraw said projection from said apertures, and thereafter shiftable about said pivot to rest said projection against the side of said cover in idle position. 50 55 60

3. The combination with a casing having a cover hinged thereto, of a flexible and shiftable arm pivoted to one side of said cover and provided with a projection thereon generally parallel to said pivot, there being corresponding apertures in the side of said cover and said casing registering with each other in closed position of the cover, and also a recess in the side of said cover equidistant with said cover-aperture from said pivot, said cover-aperture and the aperture in said casing being normally retained in registration by said arm-projection passing therethrough, said arm being conditioned to be first withdrawn by flexure thereof to withdraw said projection from said apertures, and thereafter shiftable about said pivot to displace said projection from said apertures to rest in said recess on said cover in idle position. 65 70 75

JOHN WALDHEIM.
